TRUSS

Elmer Hyatt, Cleveland, Ohio

Application February 10, 1943, Serial No. 475,359

4 Claims. (Cl. 128—106)

The present invention relates to trusses, and the principal object of the invention is to provide an improved and more efficient truss appliance for the treatment of ruptures and the like.

Accordingly one of the primary objects of my invention is to provide an improved construction in which the pad elements adapt themselves automatically and more freely to changing positions of the body without tipping or getting out of place or affecting the proper pressure action of the pads. A further object is to provide a structure in which the pressure action may be readily and conveniently increased or diminished, with a minimum of effort and without requiring the removal of the device from its wearing position.

It is also an object of the invention to devise a construction which includes belt-attaching means having an adjustable element whereby the truss may be properly adjusted and held in the correct relation to the hips of the wearer without discomfort.

It is also sought to provide a light, sanitary and inexpensive construction, which is not only inconspicuous when worn but also affords a maximum of comfort as well as relief to the wearer.

With the foregoing general objects in view, the invention will now be described in detail by reference to the accompanying drawing illustrating an appliance which embodies all the essential elements of my improvements, after which those features and combinations deemed to be both novel and patentable will be particularly set forth and claimed.

In the drawing—

Figure 1 is a perspective view, showing a truss appliance embodying the present features of my improvements;

Figure 2 is a similar, but enlarged detail view showing the rear pad element and the belt and spring member attached thereto;

Figure 3 is a sectional view of the same;

Figure 4 is an enlarged sectional detail view of the pressure or front pad element and adjacent connections;

Figures 5, 6 and 7 show plan views of washers in different sizes for the front pressure or treating pad; and

Figure 8 is a perspective view of the overlapping portions of the spring member and angular adjusting link for connecting the adjacent end of the belt.

This application is a continuation-in-part (as

to common subject matter) of my application Ser. #358,221 filed September 25, 1940.

Referring now to the accompanying drawing in detail, the improved construction is illustrated as comprising a one-piece bow-shaped frame 10 approximately semicircular in extent, which may be of any suitable light resilient material—one end of which is provided with a series of threaded openings 12 for use with a hollow or tubular thumb screw 14 having a knurled head 15, as shown in Figure 1. The other end of said frame 10 is also provided with an opening 17 for use in attaching a rear bracing pad member 18, as by means of a screw 20 (of slightly smaller diameter than the opening 17 and secured centrally to the pad 18)—as shown in Figures 2 and 3. Preferably a washer element 22 of appropriate size is fitted over the screw 20 against the outer face of the pad 18 (that is, between it and the spring member 10). Also, the pad 18 is desirably fitted with a removable soft washable cover 24, which may be provided with a conventional elastic or drawstring 25 for securing purposes.

The pressure-treating or corrective pad is of a construction comprising a roll of soft material 28, which may be so rolled as to embrace a portion of the shank or stem of a pointed nail 29, with the head 30 of the same remaining at the center of the roll of material, while preferably an outer sheath or covering 32 is applied to said roll, together with a washer element 34 of appropriate size fitted over the outer or pointed end portion of the nail for abutting engagement with the end of the adjusting screw 14 when the said outer portion of the nail (thus forming a stem for the pad) is inserted into the open end of said screw—as illustrated in Figure 4.

The end opening 12 of the spring member 10 is fitted with a clamping screw 35 which serves to clamp one end of an adjusting link 36 in overlapping relation to the spring bow 10, as represented in Figures 1 and 4. The engaging faces of the bow 10 and said link 36 are formed with radial ribs 38 and mating recesses 40, as shown in Figure 8, for cooperative action in maintaining the link 36 rigidly in any set angular relation to the bow 10. The other end of the link 36 carries a screw stud 42 adapted for removable engagement with the keyhole slot 44 of a buckle element 45 to which is adjustably looped one end of a belt strip 47—the other end of which belt strip is also provided with a buckle element 45' adapted for pivotal connection with the projecting head portion of the screw 20, and in

slightly loose play relation thereto—as illustrated in Figure 3.

The series of threaded openings 12 also enables adjustment to be made to correspond to the location of the rupture as well as the size of the person using the truss appliance.

In the use of the improved appliance, the bow frame member 10 enables the pads to be applied to the opposite sides (front and back) of the person, in the usual truss fashion—the pad 18 being applied to the back and a pad structure 28 of appropriate size being selected for application to the point of rupture in front. This pad device 28 is easily and cheaply made by winding the proper length of material, through which the nail 29 is thrust at each turn, which keeps the head of the nail at the center of the pad, and a proper size of washer 34 (corresponding to the size of pad desired) is fitted over the exposed end of the nail for engagement with the end of the screw 14 after the pointed end portion of the nail has been introduced into the open end of said screw. This is all that is necessary to hold the pad in place against any lateral or sidewise movement while in use, in which position the adjustment of the screw 14 determines at will the pressure which is applied to the pad for the corrective or treating action. Thus the size and shape of the pad 28 is determined by the kind and amount of material used as well as by the size of the washer 34, and this may of course be varied as the ruptured condition improves (allowing the muscles to gradually return to their normal condition). The nail 29 merely holds the pad 28 in place, against any up and down or sidewise shifting, with the exception of sufficient play being allowed as to both pads 18 and 28 to accommodate the contour of the body and ordinary body movements. As seen in Figure 4, there will be but very little end thrust mainly transmitted through the nail 29, the pressure on the pad being transmitted through the washer 34; and when it is desired to remove or to change the pad 28, this may be done by a slight movement of the pad merely sufficient to withdraw the nail 29 from the bore or opening of said screw 14.

One end of the belt 47 is maintained in pivotal relation to the screw 20 of the rear pad 18, as shown in Figure 2, whereas the other end of the belt is made readily detachable from the screw stud 42, as is indicated in Figure 1. The adjustable link 36 between this end of the belt and the front end of the spring bow 10 enables the truss to be fitted so as to accommodate the slant of the hips, that is, to lie flatwise against the hips instead of crowding and gouging one edge of the frame into the flesh and thereby producing an uncomfortable and irritating effect. The recesses and ribs (38 and 40), after adjusting the link 36 to the proper angle, insure rigidity of the connected parts in their adjusted and set relation.

In putting on the truss appliance, the pad 28 is applied over the exact spot where the pressure is to be applied, and then the adjusting screw 14 brought right over the nail 29 (or in alignment therewith) for telescoping over the nail, and the frame and parts then secured in this

position by attachment of the buckle 45 to the end of the adjustable link 36. Any other minor adjustments that may become necessary can thereafter be made with the truss in wearing position, by manipulation through a pocket or other place in the clothing for either shifting the pad or adjusting the pressure by a turning of the thumb screw 14, and without the necessity of removing any of the clothing for such purpose.

10 It will therefore be apparent that I have devised a very simple, and inexpensive, as well as a highly efficient type of improved construction suitable for fulfilling all the desired objects of my invention, as have been stated; and while 15 I have shown and described what I have found, from actual experience, to embody effectively the several features of said improvements, I desire to be understood as expressly reserving the right to make all changes or modifications which may 20 fairly be adjudged to fall within the spirit and scope of the following claims.

Having thus described my invention, what I claim and desire to secure by Letters Patent is:

1. A truss appliance comprising a resilient bow-shaped frame, a bracing pad connected with one end of said frame, a hollow pressure-adjusting screw threaded through the opposite end of the frame, and a treatment pad comprising a body of pad material having a stem loosely fitting within the open end of said adjusting screw.

2. A truss appliance comprising a resilient bow-shaped frame, a bracing pad connected with one end of said frame, a hollow pressure-adjusting screw threaded through the opposite end of said frame, a pressure-treatment pad comprising a pad of material having a stem loosely fitting within the open end of the adjusting screw, and a washer interposed between said screw and pad material and in sliding engagement with said stem.

3. A truss appliance comprising a resilient bow-shaped frame, a bracing pad connected with one end of said frame, a hollow pressure-adjusting screw threaded through the opposite end of said frame, and a treatment pad comprising a roll of pad-forming material provided with a stem having a head at the center of said roll and an exposed shank portion projecting in sliding telescoping relation within the open end of said screw, and a washer carried slidably by said shank portion in engagement with said roll and abutting against the open end of the adjusting screw.

4. A truss appliance comprising a continuous one-piece spring bow frame of approximately semicircular shape, a bracing pad attached to one end of said frame, a tubular pressure-adjusting element adjustably mounted on the opposite end of said frame, a treatment pad provided with a stem loosely fitting within said tubular element, a rigid link provided with a clamping screw pivotally connecting the link to the end of said frame carrying said adjusting element and adapted to secure said link at various angles with relation to the frame, and a belt connecting the free end of said link with the other end of said frame.

ELMER HYATT.
